SWIMMING APPLIANCE

Nicholas Squicciarini, Plainfield, N. J.

Application February 19, 1937, Serial No. 126,682

5 Claims. (Cl. 9—21)

The present invention relates to new and useful improvements in swimming appliances and has for its primary object to provide, in a manner as hereinafter set forth, a device which is adapted to be mounted on a swimmer's foot and which includes novel means in the form of a pair of swinging blades to materially assist the swimmer in propelling himself through the water.

Another very important object of the invention is to provide a swimming appliance of the aforementioned character comprising novel means for connecting the blades together for swinging movement in opposite directions in unison.

Still another very important object of the invention is to provide an appliance of the character described embodying a novel construction and arrangement whereby the swimmer may walk on the device without damaging the blades or other parts.

A still further important object of the invention is to provide a swimming appliance of the character set forth which may be expeditiously adjusted to fit different sizes of feet.

Other objects of the invention are to provide a swimming appliance of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in top plan of a swimming appliance constructed in accordance with the present invention, showing the blades in open position.

Figure 2 is a view in side elevation thereof with a portion broken away in section.

Figure 3 is a bottom plan view of the invention.

Figure 4 is a view in vertical longitudinal section through the appliance, taken substantially on the line 4—4 of Fig. 1.

Figure 5 is a cross sectional view, taken substantially on the line 5—5 of Fig. 1.

Figure 6 is a view in front elevation of the invention with the gear housing removed.

Figure 7 is a detail view in perspective of one of the substantially channel or U-shaped side bars.

Figure 8 is a detail view in perspective of one of the cushions.

Referring now to the drawings in detail, it will be seen that the embodiment of the invention which has been illustrated comprises a pair of substantially channel shaped side bars 1 of suitable metal the flanges of which project inwardly, as illustrated to advantage in Fig. 5 of the drawings. Rigidly secured between the end portions of the side bars 1 are metallic blocks 2. The upper edges of the blocks 2 are substantially flush with the upper flanges of the side bars 1 but said blocks project below the lower flanges of said side bars 1. This is also shown to advantage in Fig. 5 of the drawings.

Rigidly secured on the blocks 2 and projecting forwardly and rearwardly therebeyond is a metallic foot plate 3. The foot plate 3 also projects beyond the side bars 1. Formed in the projecting longitudinal marginal portions of the foot plate 3, adjacent the forward end of said foot plate, are pairs of slots 4. The slots 4 are adapted to receive a suitable strap 5 for securing the forward end portion of the device to the foot. The strap 5 may be secured in either pair of slots 4 according to the length of the swimmer's foot. Formed in the rear portion of the plate 3 are pairs of slots 6 which are substantially similar to the slots 4. The reference numeral 7 designates an arcuate, metallic heel plate having depending hooks 8 on its end portions which are engageable selectively in the pairs of slots 6 in the manner shown to advantage in Fig. 2 of the drawings. A slotted bracket 9 is rigidly secured to the lower portion of the arcuate heel plate 7 at the rear thereof for receiving a securing screw 10. The securing screw 10 is adapted to be threaded selectively in openings 11 which are provided therefor in the foot plate 3 for securing the rear portion of the arcuate heel plate 7 in position. To mount the arcuate heel plate 7 in position, the hooks 8 are inserted through the desired pair of slots 6, after which said heel plate 7 is moved forwardly in a manner to engage said hooks beneath the foot plate 3. The screw 10 is then threaded into one of the openings 11 through the slotted bracket 9 for securing the heel plate 7 against longitudinal movement.

Journalized in the blocks 2 and extending therethrough is a pair of spaced, parallel, longitudinally extending shafts 12. Fixed on the end portions of the shafts 12, forwardly and rearwardly of the blocks 2, are meshed gears 13 through the medium of which said shafts are connected together for rotary movement in opposite direc-

tions in unison. Front and rear metallic housings 14 and 15, respectively, are mounted on the blocks 2 beneath the projecting end portions of the foot plate 3 and enclose the gears 13.

5 Mounted on the shafts 12 for rotation therewith are pairs of adjustable arms 16. The arms 16 are secured in adjusted position on the shafts 12 through the medium of set screws 17. Mounted on the pairs of arms 16 are metallic blades 18.

10 Cushions 19 of suitable material, preferably rubber, are mounted on the lower flanges of the side bars 1 for engagement by the arms 16 when the blades 18 swing to open position (see Fig. 5). Mounted for swinging movement on the housing 15 is a latch 20 which is engageable beneath the adjacent blade 18 for releasably securing the blades in open position. A thumb lever 21 is provided for actuating the latch 20. The thumb lever 21 is engageable in a notched keeper 22 on 15 the housing 15 for releasably securing said lever and the latch 20 against swinging movement. The arcuate heel plate 7 is provided with suitable slots 23 for receiving a strap, as at 25, for securing the rear end of the device to the foot.

20 It is thought that the manner of using the appliance will be readily apparent from a consideration of the foregoing. The strap 5 and the arcuate heel plate 7 are inserted in the desired pairs of slots 4 and 6 and the device is secured to 25 the foot of the swimmer. Of course, one of the devices is mounted on each foot. As the swimmer kicks out with his legs, the blades 18 swing to open position, as shown in full lines in Fig. 5 of the drawings, in a manner to materially assist 30 said swimmer in propelling himself through the water. As the swimmer draws his legs forwardly for the next power stroke the blades 18 swing to the position shown in dotted lines in Fig. 5 of the drawings for reducing resistance to the water to a minimum. The cushions 19 engage the arms 16 35 for arresting the blades 18 on their outward swinging movement, said cushions assuring quiet operation. When the user desires to walk with the appliance on his feet, the blades 18 are swung to open position and secured through the medium 40 of the latch 20. With the blades 18 thus secured in open position the blocks 2 will engage the ground and support the weight of the user. A longitudinal reenforcing plate 24 is rigidly secured beneath the rear end portion of the foot 45 plate 3. As shown in Fig. 4 of the drawings, the reenforcing plate 24 is provided with threaded openings aligned with the openings 11 for the reception of the screw 10.

50 It is believed that the many advantages of a swimming appliance constructed in accordance with the present invention will be readily understood and although a preferred embodiment of the device is as illustrated and described, it is to

be understood that changes in the details of construction and in the combination and arrangement of parts may be resorted to which will fall within the scope of the invention as claimed.

What is claimed is:—

5 1. A swimming appliance comprising a foot plate, means for securing said foot plate to the foot of a swimmer, a pair of parallel shafts journaled to and beneath the foot plate, blades fixed on said shafts, and means connecting the shafts 10 together for rotation in opposite directions in unison.

2. A swimming appliance comprising a foot plate, means for securing said foot plate on the foot of a swimmer, a pair of blocks fixed beneath 15 the foot plate at longitudinally spaced points, a pair of parallel shafts journaled in said blocks and extending therethrough, gears fixed on the end portions of the shafts, said gears being meshed with each other for connecting the shafts 20 together for rotation in opposite directions in unison, housings mounted on the blocks and enclosing the gears, and blades fixed on the shafts between the blocks.

25 3. A swimming appliance comprising a foot plate, means for securing said foot plate to the foot of a swimmer, a pair of longitudinally spaced blocks fixed beneath the foot plate, a pair of parallel shafts journaled in said blocks, means for connecting said shafts together for rotation in 30 opposite directions in unison, blades fixed on the shafts and adapted for swinging movement to open and closed position beneath the foot plate, and means for releasably securing said blades in open position.

35 4. A swimming appliance comprising a foot plate, said foot plate having slots in its longitudinal marginal portions, an arcuate heel plate detachably mounted on the foot plate, said heel plate including depending hooks engageable in 40 the slots and slidably beneath the foot plate for securing said heel plate in position thereon, means for securing the heel plate against sliding movement on the foot plate, and a pair of blades mounted beneath the foot plate and adapted for 45 swinging movement to open and closed position.

50 5. A swimming appliance comprising a pair of substantially channel shaped side bars, metallic blocks secured between the end portions of said side bars, a foot plate secured to said blocks, means for securing the foot plate to the foot of a swimmer, a pair of spaced, parallel shafts journaled in the blocks, arms fixed on said shafts, blades fixed on said arms and adapted for swinging movement to open and closed position beneath the foot plate, and cushions mounted on 55 the side bars and engageable by the arms when the blades swing to open position.

NICHOLAS SQUICCIARINI.
